COLLAPSIBLE TUBE

Walter Zahara, Chicago, Ill.

Application January 2, 1943, Serial No. 471,097

2 Claims. (Cl. 222—107)

1

The present invention relates to collapsible tubes for dispensing tooth paste, salves, creams, paste, etc., and has for its main object the provision of a tube to be made out of oiled or impregnated paper, or suitable cellulosic material, and which may be suitably formed out of a single blank.

A still further object of the present invention is the provision of a tube of the character indicated in which marginal folds, which in the completed tube will form one of the walls thereof, may retain therebetween metallic, or other suitable strip for the purpose of facilitating the rolling of the tube at one end thereof and for retaining the roll in position as the same is being made for the purpose of ejecting the contents of the tube through the usual neck at the opposite end of the tube.

It is a well known fact that fabric material, such as impregnated paper or cellulose has a tendency to assume its original position, and thus a tube made of such a material would have a tendency to unwind at its roll at one end of the tube, therefore a further object of the present invention is to provide means whereby the roll when formed would maintain its shape without unwinding.

A still further object of the present invention is the provision of a tube of the character indicated and which may be made out of a single blank sheet, with suitable creases provided therein to facilitate folding of the blank, whereby the tube may assume polygonal formation on transverse cross section, with one end of said blank suitably slit to provide a plurality of flaps, which, when folded, may provide transverse end wall for the tube.

A still further object of the present invention is the provision of a tube of polygonal formation on cross section, to facilitate collapsibility of the tube and rolling of one end thereof to eject the contents of the tube.

A still further object of the present invention is the provision of a method whereby a tube of the character indicated may be formed.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application, and in which like designating characters re-

2

fer to corresponding parts throughout the several views;

Fig. 1 is a side elevational view of the tube;

Fig. 2 is a longitudinal cross sectional view of the tube on an enlarged scale, taken on line 2—2 of Fig. 1, with neck and neck retaining member in elevation;

Fig. 3 is an enlarged cross sectional view on line 3—3 of Fig. 1;

Fig. 4 is an elevational discharge end view of the tube;

Fig. 5 is a perspective view, on a reduced scale, of the end wall retaining fixture with the neck integrally formed therewith; and

Fig. 6 is an elevational view of the blank, on a reduced scale, out of which the tube is formed.

Referring in detail to the present drawing there is shown therein a rectangular blank 10, made out of impregnated paper, cellulose, or other cellulosic material. A plurality of longitudinal creases 11 is made in said blank 10, to divide said blank longitudinally into a pair of marginal folds 12, four narrower strips 13, a pair of which is disposed adjacent to each of the said marginal folds 12, and a central strip 14 interposed between the two pairs of strips 13. Strips 13 are of equal width, but are narrower than said marginal folds 12 and strip 14.

One end of said blank 10 is incised, as at 15, to effect at the ends of folds 12, and strips 13 and 14, a plurality of flaps 16. Said incisions 15 extend to the dotted line 17 along which said flaps 16, when bent transversely and perpendicularly to their respective folds 12 and strips 13 and 14 will constitute the end wall 18 in the finished tube 19.

For the sake of clearness sections of the wall in the completed tube are designated with the same corresponding characters as folds 12 and strips 13 and 14.

When the blank, shown in Fig. 6, has been prepared in accordance with the hereinabove description, the same is bent longitudinally and along creases 11. A metallic strip 20, preferably of ductile or pliable character, is interposed between marginal folds 12, and thereupon said marginal folds are cemented to each other. Said strip 20 does not extend to wall 18 but terminates short thereof, but the opposite end thereof is continuous with the opposite end of tube 19.

When the side wall of the tube has been formed as aforesaid, several flaps 16 are thereupon bent perpendicularly to the body portion of the tube, first preferably bending the narrower flaps 16, those extending from strips 13, thereupon bend-

ing the central flap 16, the one extending from strip 14, and thereupon bending the double flap 16 extending from the two overlapping marginal folds 12. All these flaps 16 are cemented to each other and pressed, so that in the finished tube they will constitute the end transverse wall 18, which will present a solid, compact and homogeneous formation, unlike the loose and exaggerated condition thereof illustrated in Fig. 2. Thereupon in said wall 18 and centrally thereof a central aperture 21 is made through which an externally threaded neck 22 extends for the purpose of receiving a usual cap. Said neck 22 is integrally formed with a polygonal plate 23, preferably made of suitable plastic material, which is positioned in contactual relation with the interface of said wall 18, and by its edges with the several portions of the side wall thereof. The contents of the tube will maintain said plate 23 in its operative position. Said plate 23 and neck 22 are provided with bore 24 through which contents of the tube are ejected.

From the hereinabove description it will be seen that the tube, being of polygonal formation, will present a plurality of corners or angles 25 made along creases 11, which facilitate collapsibility of the tube, eliminating drag or distortion which usually occurs in cylindrical tubes.

At the closed end of the tube the usual roll is made, the outermost edge of which is clamped within a U-shaped clasp 21. At that end of the tube wider wall sections 12 and 14 as well as the two adjacent pairs of wall sections 13 are in contactual relation. The two opposed angles between the adjacent wall sections 13 completely close, and angles 25 between sections 12 and 14 and the adjacent sections 13 completely open as the wall of the tube is progressively wound in roll 26, as is indicated in Fig. 1, for the purpose of ejecting the contents of the tube through bore 24.

Due to the pliable or ductile nature of strip 20 roll 26, once made, will be retained in position, notwithstanding the tendency of fibrous material of the wall of the tube to assume its original formed position. Since the several sections of the walls of the tube, as well as strip 20, are straight, and not arcuate as in cylindrical tubes, the formation of roll 26 will progress without any undue distortion or drag upon the wall of the tube. Likewise, due to the fact that the several sections of the wall of the tube are straight, the contents of the tube will not tend to be retained within roll 26 as the same is progressively made, as oftentimes occurs in cylindrical tubes.

It is further observed that in view of the fact that plate 23 is polygonal and by its margin in a frictional contactual relation with the side wall of the tube, the same will not be displaced when

cap is placed upon or removed from neck 22, and therefore need not be anchored in any manner to the body of the tube.

While there is described herein a preferred embodiment of the present invention, it is nevertheless to be understood that minor changes may be made therein without departing from the spirit and scope of the invention as claimed.

What I claim as new is:

1. A flexible container, adapted to be rolled to flatten the same and thereby dispense its contents, and comprising an elongated sheet of cellulose material folded to form a body of general hexagonal form in cross section and having a top wall, two opposed side wall sections of the body being wider than the remaining four side wall sections thereof and one of them consisting of similar members on opposite edges of the sheet overlapped substantially throughout the width of said members and adhesively secured together, a pliable metallic strip disposed and secured centrally of and between said overlapped members and extending longitudinally of the body from a point near the top wall to the lower end of the body, the lower end portion of the body being gradually flattened in flared form and having its lower extremity secured in completely flattened and folded condition to form a roll being disposed parallel with the lower end of the body, said roll being disposed parallel with the wider side wall sections of the body, and a discharge neck secured to the top wall.

2. A flexible container, adapted to be rolled to flatten the same and thereby dispense its contents, and comprising an elongated sheet of cellulose material folded to form a body of general hexagonal form in cross section and having a flat top wall provided with a central opening, two opposed side wall sections of the body being wider than the remaining four side wall sections thereof and one of them consisting of similar members on opposite edges of the sheet overlapped substantially throughout the width of said members and adhesively secured together along one side of the body, a pliable metallic strip disposed and secured centrally of and between said overlapped members and extending longitudinally of the body from a point near the top wall to the lower end of the body, the lower end portion of the body being gradually flattened in flared form and having its lower extremity secured in completely flattened and folded condition to form a roll being disposed parallel with the lower end of the body, said roll being disposed parallel with the wider side wall sections of the body, and a discharge neck fitted in and projecting upwardly through the opening in the top wall.

WALTER ZAHARA.
